(57) CLAIM

The ornamental design for a crucible, as shown and described.

DESCRIPTION

FIG. 1 is a front view of the first embodiment of a crucible showing our design;
 FIG. 2 is a rear view thereof;
 FIG. 3 is a top plan view thereof;
 FIG. 4 is a bottom plan view thereof;
 FIG. 5 is a right side view thereof;
 FIG. 6 is a left side view thereof;
 FIG. 7 is a cross-sectional view taken along line 7-7 of FIG. 3 thereof;
 FIG. 8 is a perspective view thereof;
 FIG. 9 is a front view of the second embodiment of a crucible showing our design;
 FIG. 10 is a rear view thereof;
 FIG. 11 is a top plan view thereof;
 FIG. 12 is a bottom plan view thereof;
 FIG. 13 is a right side view thereof;
 FIG. 14 is a left side view thereof;
 FIG. 15 is a cross-sectional view taken along line 15-15 of FIG. 11 thereof; and,
 FIG. 16 is a perspective view thereof.
 In the drawings the broken lines are for the purpose of illustrating environment only and form no part of the claimed design.
